UNITED STATES PATENT OFFICE

162,697

PHONOGRAPH TONE ARM OR THE LIKE

Clifford Brooks Stevens, Milwaukee, Wis., assignor to Webster Electric Company, Racine, Wis., a corporation of Delaware

Application December 23, 1950, Serial No. 13,557

Term of patent 14 years

(Cl. D26—14)

To all whom it may concern:

Be it known that I, Clifford Brooks Stevens, a citizen of the United States, residing at 8041 Gray Log Lane, Milwaukee, Milwaukee County, Wisconsin, have invented a new, original, and ornamental Design for a Phonograph Tone Arm or the like, of which the following is a specification, reference being had to the accompanying drawing, forming a part hereof.

Fig. 1 is a perspective view of the phonograph tone arm or the like, embodying my new design;

Fig. 2 is a top plan view thereof; and

Fig. 3 is a side elevational view.

I claim:

The ornamental design for a phonograph tone arm or the like, substantially as shown.

CLIFFORD BROOKS STEVENS.
